(57) **CLAIM**

The ornamental design for an elongated rail body of a tool holding device, as shown and described.

DESCRIPTION

FIG. 1 is a top perspective view of an elongated rail body of a tool holding device showing my new design;

FIG. 2 is a bottom perspective view thereof;

FIG. 3 is a front elevational view thereof, the rear elevational view being a mirror image;

FIG. 4 is a top plan view thereof; and,

FIG. 5 is a right elevation view thereof, the left side elevational view being a mirror image.

The broken line showing the elongated rail body of a tool holding device in FIGS. 1-3 are included for the purpose of showing environmental structure and form no part of the claimed design.
